US0D1035656S

(12) **United States Design Patent** (10) Patent No.: **US D1,035,656 S**
(45) Date of Patent: ** Jul. 16, 2024

(54) **WIRELESS COMMUNICATION MODULE FOR AUTOMOBILE**

(71) Applicant: **LG Electronics Inc.**, Seoul (KR)

(72) Inventor: **Changsik Woo**, Seoul (KR)

(73) Assignee: **LG ELECTRONICS INC.**, Seoul (KR)

(**) Term: **15 Years**

(21) Appl. No.: **35/517,356**

(22) Filed: **May 30, 2022**

(80) **Hague Agreement Data**

Int. Filing Date: **May 30, 2022**

Int. Reg. No.: **DM/222275**

Int. Reg. Date: **May 30, 2022**

Int. Reg. Pub. Date: **Jun. 2, 2023**

(30) **Foreign Application Priority Data**

Dec. 10, 2021 (KR) 30-2021-0059772

(57) **CLAIM**

The ornamental design for a wireless communication module for automobile, as shown and described.

DESCRIPTION

1. Wireless communication module for automobile

1.1 : Perspective

1.2 : Front

1.3 : Back

1.4 : Left

1.5 : Right

1.6 : Top

1.7 : Bottom

Reproduction 1.1 is a perspective view of the wireless communication module for automobile; reproduction 1.2 is a front view thereof; reproduction 1.3 is a back view thereof; reproduction 1.4 is a left view thereof; reproduction 1.5 is a right view thereof; reproduction 1.6 is a top view thereof; reproduction 1.7 is a bottom view thereof; this design is for a wireless communication module whose pin shapes of the surface are unified; this design can apply to various communication modules regardless of the design method of the communication module.
